Fixture and Support Therefor

Eric V. Haffling, Stratford, Conn., assignor to
Columbia Phonograph Company, Inc., Bridge-
port, Conn., a corporation of New York

Application October 25, 1932, Serial No. 639,450

2 Claims. (Cl. 248—20)

This invention relates to new and useful improvements in fixtures and their supports or holders.

An object of the invention is to provide an improved means whereby fixtures such as tumbler holders, soap dishes, towel racks and the like may be firmly secured to a suitable supporting means.

Another object is to provide a device as stated and which is of simple construction and which is 10 easily used or set up and which may be manufactured and sold at a reasonable price.

Other objects and advantages will become apparent from a consideration of the following detailed description taken in connection with the 15 accompanying drawing wherein a satisfactory embodiment of the invention is shown. However, it will be understood that the invention is not limited to the details disclosed but includes all such variations and modifications as fall within the spirit of the invention and the scope of the appended claims.

In the drawing:

Fig. 1 is a perspective view showing the parts in position ready to be assembled;

Fig. 2 is a detail view in side elevation and on an enlarged scale and showing a fixture supported in accordance with the present invention; and

Fig. 3 is a detail sectional view taken substantially along the line 3—3 of Fig. 2.

Referring in detail to the drawing, at 5 is shown 30 a fixture which while it may be in the form of a soap dish, towel rack or the like, is for the purpose of illustration disclosed as a tumbler holder. The fixture 5 includes a bottom 6, a side wall 7, and 35 at its upper edge is provided with an outwardly extending bead 8. Also, the bottom of the fixture may be re-inforced as by ribs or raised portions 9.

On the outer surface of its wall 7 the fixture is 40 provided with an enlargement 10, the opposite outer vertical edges of which provide shoulders 11 inclining transversely in opposite directions or converging in the direction of the body of the fixture. These shoulders also incline or taper 45 vertically whereby their vertical planes converge at a point below the fixture. Between the portions forming the shoulders 11 the enlargement 10 is cut away to provide a recess 12, the purpose of which will later appear. It is to be noted that 50 in the vicinity of the enlargement 10 the bead 8 is also enlarged as at 13 whereby its outer edge projects beyond said enlargement 10.

A clip 14 is also employed and this clip is preferably formed of metal and includes a connecting portion 15 off-set at spaced points 16 and serving

to connect a pair of flanges 17 which also converge transversely and vertically in accordance with the convergence of the shoulders 11. This metal clip 14 may be secured to a surface of any suitable support 18 as by means of screws 19 passed through openings 20 in the connecting portion 15 of the clip. These screws are drawn up tight whereby the connecting portion of the clip is drawn into firm engagement with a surface of the support 18. 60

With the clip 14 secured to a surface of a support as above described the fixture 5 is easily mounted. The relationship of the enlargement 10 of the fixture to the space between the flanges 17 of the clip is such that the shoulders 11 of the enlargement wedgingly engage the inner surfaces of the flanges 17. As the enlargement 10 is forced into the space between the flanges of the clip the enlarged or extending portion 13 of the bead 8 is drawn into engagement 75 with the forward surface of the support 18 with the result that there is a tendency on the part of the fixture to move outwardly from the said support and this is permitted to a limited extent since the off-sets 16 in the connecting 80 portion 15 of the clip render said portion slightly flexible. As these portions of the clip are drawn forwardly owing to the engagement of the bead portion 13 with the support the flanges of the clip more tightly grip the shoulders 11 85 whereby the fixture is firmly held. In Fig. 2 it will be noted that when the device is wedged in place the portion 13 of the bead remains spaced slightly above the upper edges of the flanges 17. The constant tendency of the clip 90 is to maintain this bead portion 13 in firm engagement with the face of the support, this action resulting from the fact that the clip is slightly sprung when the fixture is forced downwardly to carry its enlargement 10 into the clip 95 after the bead portion 13 has engaged the support. This constant pressure between the clip and the fixture and the fixture and the support results in the fixture being very firmly held in place. 100

Having thus described the invention, what is claimed is:

1. In combination, a fixture having a pair of shoulders, a holder having a pair of flanges, said flanges adapted to embrace said shoulders, said fixture having a bead portion projecting beyond said shoulders, said holder including a body portion carrying said flanges, said body portion including a central portion and outwardly off-set edge portions carrying said flanges whereby said 110

flanges are resiliently mounted when said central body portion is secured against a support, means securing said central body portion to a support with said flanges projecting outwardly therefrom, and said flanges spaced apart to receive said shoulders and adapted to yield outwardly on movement of said shoulders into the holder after said bead portion engages the sup-

port whereby to yieldingly press said bead portion into engagement with the support.

2. The structure of claim 1, wherein said shoulders are connected together by a concave arcuate portion thereby leaving an open space in front 80 of the central portion of the holding means.

ERIC V. HAFFLING.
